[57] CLAIM

The ornamental design for a chair, as shown and described.

DESCRIPTION

FIG. 1 is a front perspective view of a chair showing my design;

FIG. 2 is a rear perspective view;

FIG. 3 is a front elevational view;

FIG. 4 is a rear elevational view;

FIG. 5 is a top plan view of the chair of FIG. 3; and FIG. 6 is a left side elevational view of the chair shown in FIG. 3, the right side elevational view being substantially identical thereto.

FIG. 1

FIG. 2
